CLAIM

The ornamental design for a modular audio-video cassette cabinet, as shown and described.

DESCRIPTION

FIG. 1 is a front elevational view of a modular audio video cassette cabinet showing our new design;

FIG. 2 is a rear elevational view thereof;

FIG. 3 is a left side elevational view, the opposite side being a mirror image;

FIG. 4 is a top plan view thereof;

FIG. 5 is a bottom plan view thereof; and,

FIG. 6 is a perspective view of a typical drawer with a divider and the cabinet housing removed for convenience and illustration.

FIG. 1

FIG. 2

FIG. 3
